TWO COMPARTMENT MAILBOX

Claude J. Amo, Ogdensburg, N. Y.

Application April 20, 1948, Serial No. 22,179

6 Claims. (Cl. 232—24)

1

This invention relates to a mail box and more particularly to an individual-user type of mail box having a letter receiving compartment and a separately accessible compartment for receiving mail such as small packages and rolled newspapers or magazines.

It is an object of this invention to provide a new and improved individual-user type of mail box serving all the functions of a conventional mail box and providing, in addition, a repository for mail not capable of being received in the conventional type of mail box whereby such mail can be placed in a safe place and protected from possible exposure to the weather.

It is another object of this invention to provide such a mail box having, in a unitary structure, a letter receiving compartment and a separate compartment for receiving mail bulkier than letter mail, such as small packages and rolled newspapers or magazines, said separate compartment being accessible without permitting access to said letter receiving compartment.

It is a further object of this invention to provide a mail box of the type referred to which is ornamental in appearance, is of sturdy construction, and amply protects the contents thereof from the elements.

These and other objects and advantages of this invention will become apparent from the following detailed description taken in conjunction with the attached drawings in which:

Fig. 1 is a perspective view of a mail box constructed in accordance with the teaching of my invention, the front wall and covers of said mail box being shown in closed position;

Fig. 2 is a view similar to Fig. 1 with the top cover shown raised and the front wall slightly ajar to expose the interior of the mail box;

Fig. 3 is a view similar to Fig. 1 showing component parts of the mail box in dis-assembled relationship;

Fig. 4 is a sectional view taken as indicated along line 4—4 of Fig. 6;

Fig. 5 is a sectional view taken as indicated along line 5—5 of Fig. 6; and

Fig. 6 is a sectional view taken as indicated along line 6—6 of Fig. 5.

Referring generally to the embodiment of my invention which I have illustrated in the drawings, the separate compartment for receiving mail not capable of being received in the letter receiving compartment is located at the lower front portion of the mail box and is defined by an interior partition wall and also by portions

2

of walls of the letter receiving compartment. The interior partition wall is also a wall of the letter receiving compartment and thus blocks off access to the letter receiving compartment even though independent access is had to the separate compartment. Forming of the separate compartment from an interior partition wall plus portions of walls of the letter receiving compartment results in a compact unitary structure of pleasing appearance and one that is not objectionably large.

In closed position, as shown in Figure 1, the mail box is seen as having a front wall member 10, which could be termed a panel or door, which includes a plane upper portion 11 and a bulged out lower portion 12. Viewed edgewise, see Figures 2, 3 and 6, this lower portion 12 is of arcuate shape and, as is explained in greater detail hereinafter, forms part of the separate repository or compartment for mail bulkier than letter mail. The front wall 10, like other wall members to be described, is preferably made of suitable thin gauge sheet metal.

The upper portion 11 of front wall 10 has hinge leafs 13 formed integrally along one edge thereof which interleave with hinge leafs 14 formed integrally on side wall member 15 to form a hinge support for front wall 10 thus allowing the front wall, or door, to be opened as is shown in Figure 2. For security a lock mechanism is provided and, while the particular type lock mechanism is not part of the present invention, I have illustrated a combination lock 16 which, when released, enables the catch release slide 17 to be moved to the right and releases the catch 18 allowing the front wall to be opened. Opening of the front wall permits ready access to the letter receiving compartment which will now be described.

Referring particularly to Figure 3 of the drawings, two oppositely disposed spaced apart side walls 15 and 19 are shown as being connected to a back wall 20 and a bottom wall 21. Side wall 15 is provided with an inwardly extending flange 22 which extends around the periphery of the side wall as shown in Figure 3 and side wall 19 is likewise provided with an inwardly extending flange 23 which extends around the greater portion of the periphery of this side wall; again see Figure 3. Connection of the back wall 20 and the bottom wall 21 to the side walls 15 and 19 is made along these flanges 22 and 23 and, while no particular type of connection has been shown, it will be understood

that the connection could be, for example, spot welding, metal rivets or simply metal screws.

The top wall of the letter receiving compartment is indicated at 24 and this wall member is connected to portions of flanges 22 and 23 which extend along the top edges of side walls 15 and 19 as shown in the drawings. It will be observed that the top wall 24 is peaked, i. e. had a ridge line 25, whereby moisture, such as rain, will be shed readily instead of collecting on the top of the mail box. The top wall is provided with a drop slot 26 extending substantially the length of the top. A cover flap 27 is hingedly connected to a pivot rod 28 located adjacent the ridge line 25 and this cover flap, in closed position, conceals the drop slot 26. For additional protection against moisture, etc. getting into the mail box from the top, the cover flap is provided with downwardly extending side flanges 29 and 30, and the cover flap extends beyond the front edge 31 of top wall 24; see Figure 6. A mail indicator 32 is pivotally mounted on the cover flap and opposite sides of this indicator can be colored differently to provide an indication, depending upon which way the indicator is turned, as to whether or not the mail box contains mail.

The lower front portion of side wall 15 is recessed as indicated at 33, see Figure 3, and the lower front portion of side wall 19 is correspondingly recessed as indicated at 34. At these recessed portions the flanges 22 and 23 are arc-shaped in edge view and to these arc-shaped portions of these flanges the correspondingly curved partition wall 35 is connected. As stated before, the front wall 10 has an upper plane portion 11 and a bulged out, or offset, lower portion 12. The bulge out, or offset, starts at line 36. Bottom wall 21 has a rear plane portion 37 and a forward bulged down, or offset, portion 38. The bulge down, or offset, starts at line 39. Curved partition wall 35 has an edge 46 adjacent line 39 and an edge 47 adjacent line 36, when the front wall 10 is closed. Partition wall 35 extends between edges 46 and 47 and also extends between the side walls 15 and 19 thus closing off access to the letter receiving compartment at the lower front portion of this compartment, i. e. throughout the length of the portions of flanges 22 and 23 extending along the recesses 33 and 34.

From the foregoing description it can be seen that the letter receiving compartment is defined by parallel plane side walls 15 and 19, back wall 20, the plane portion 37 of bottom wall 21, the peaked top wall 24, curved partition wall 35, and the plane portion 11 of front wall 10 (when the latter is in closed position). These various components can be readily viewed in Figure 3 and, in assembled relation, in Figures 1 and 2. Of these components, only the front wall 10 is movable and when this wall is locked shut the letter receiving compartment is substantially inaccessible. However, when the front wall is unlocked and swung open it is easy to reach into the letter compartment and remove the mail.

The curved partition wall 35, the curved lower portion 12 of front wall 10, and the curved forward portion 38 of bottom wall 21 complement each other to form a tubular compartment which extends the length of the mail box at the lower front thereof. As viewed in Figure 6, these respective curved parts are arcs of a circle and, together, make a cylindrical compartment. Pivotal cover flaps 40 and 41 are provided at each end of this compartment. Considering cover flap 40 as an example, this cover flap is pivotally con-

nected to side wall 19 at 42 and is provided with a finger hole 43 whereby the cover flap can be readily drawn aside to expose the tubular compartment and permit insertion or withdrawal of mail matter. Cover flap 41 is similarly operated and, in practice, when it is desired to swing front wall 10 outward, cover flap 41 is first swung out of the way. Having two cover flaps which can be swung clear of the ends, or mouths, of the tubular compartment makes it easy to retrieve objects from within this compartment since they can be pushed through, if necessary, from one end to the other.

Even though access is readily had to the tubular compartment, the letter receiving compartment is not exposed because the partition wall 35, which is a wall common to both the letter receiving compartment and the tubular compartment, extends from adjacent bottom wall 21 (i. e. edge 46 is adjacent line 39) to adjacent front wall 10 (i. e. edge 47 is adjacent line 36) thus effectively closing off the letter compartment as long as the front wall 10 is in closed position, i. e. in door shut position. Figure 6 illustrates this particularly well. From line 39 the curved portion 38 of bottom wall 21 extends to edge 44 and the curved portion 12 of front wall 10 extends from line 36 to edge 45. As shown in Figure 6, these edges 44 and 45 abut when the front wall 10 is shut and thus complete the separate tubular compartment.

To facilitate attaching the mail box to a support surface, the back wall 20 is provided with openings 48 to receive headed screws, bolts, etc. should such means of mounting be employed.

It will thus be seen that I have illustrated and described a unitary structure mail box which is of sturdy construction and attractive appearance and which serves as a repository for dual types of mail, permitting one type of mail to be removed without affording access to the other type. As a matter of fact, the separate compartment herefore described can also serve as a repository for non-mail matter, such as newspapers delivered by carrier boys, and thus has a wider usage than merely as a mail repository.

In the embodiment of my invention set forth in this specification the separate compartment is shown and described as being cylindrical in shape, i. e. of circular cross-section, whereby the wall members 12, 35 and 38 are circular arcs in edge view. This is a desirable shape for this compartment since it is a shape adapted to receive readily mailing tubes, rolled papers, etc. However, the separate compartment need not be exactly circular in cross-section. The important thing is that the interior partition wall block off access to the letter compartment when the front wall is closed.

Accordingly, while I have shown and described a particular embodiment of my invention, I wish it to be understood that I do not intend to be restricted solely thereto but that I do intend to cover all modifications thereof which would be readily apparent to one skilled in the art and which come within the spirit and scope of my invention.

Having thus described my invention, what is claimed as new and desired to be secured by Letters Patent is:

70 I claim:

1. A two compartment mail box comprising walls defining a letter receiving compartment, two of said walls being exterior walls of substantially equal length and positioned at an angle to each other, a partition wall extending length-

wise of said two walls and contacting each of them along a line extending in a direction lengthwise of said walls, and a wall member extending from each of said two walls in a direction substantially at right angles to the length of said walls, said wall members having meeting edges in contact with each other and defining, together with said partition wall, an auxiliary compartment for receiving mail bulkier than letter mail, said auxiliary compartment having an end opening whereby said mail is inserted or withdrawn in a direction lengthwise of said partition wall and wall members.

2. A two compartment mail box adapted to be positioned in upright position, said mail box comprising walls defining a letter receiving compartment, one of said walls being a substantially vertical wall and another of said walls being a substantially horizontal wall, each of said vertical and horizontal walls having a curved wall member extending therefrom, said wall members being of corresponding length and having edges closely adjacent each other throughout said length, and a partition wall extending between and contacting said vertical and horizontal walls, said partition wall being substantially equal in length to said curved wall members and defining, together with said wall members, an auxiliary compartment for receiving mail bulkier than letter mail, said auxiliary compartment having an opening at one end thereof whereby said mail is inserted or withdrawn in a direction lengthwise of said compartment.

3. A two compartment mail box comprising walls defining a letter receiving compartment, one of said walls being a planar front wall and another of said walls being a planar bottom wall, said walls being of substantially equal length and each having an arcuate wall member extending therefrom in a direction substantially at right angles to the length of the wall, said arcuate wall members having edges closely adjacent each other throughout the length of said walls, and an arcuate partition wall extending between and contacting said front and bottom walls, said partition wall defining, together with said arcuate wall members, a tubular auxiliary compartment for receiving mail bulkier than letter mail, said auxiliary compartment having an end opening whereby mail is inserted or withdrawn in a direction extending axially of said compartment.

4. A two compartment mail box comprising walls defining a letter receiving compartment, said walls including spaced oppositely disposed end walls and exterior walls extending between said end walls, two of said exterior walls being positioned at an angle to each other and each of said two walls having a wall member extending therefrom, said wall members having edges closely adjacent each other substantially the distance between said spaced end walls, and a partition wall extending between and contacting said oppositely disposed end walls and said two exterior walls, said partition wall, together with said ex-

tending wall members, defining an auxiliary compartment for receiving mail bulkier than letter mail, at least one of said end walls being cut-away to provide an opening for said auxiliary compartment, said opening being located adjacent said end wall whereby mail is inserted or withdrawn from said auxiliary compartment from an end of said mail box.

5. A two compartment mail box comprising walls defining a letter receiving compartment, said walls including spaced oppositely disposed side walls, a front wall, and a bottom wall, each of said front and bottom walls having a wall member extending therefrom and said wall members having edges closely adjacent each other substantially throughout the distance between said spaced side walls, and a portion wall extending between and contacting said side walls, front wall and bottom wall, said portion wall, together with said extending wall members, defining an auxiliary compartment for receiving mail bulkier than letter mail, each of said side walls being cut-away to provide oppositely disposed end openings for said auxiliary compartment whereby mail is inserted or withdrawn from said auxiliary compartment from either side of said mail box.

6. A mail box comprising an upright box-like letter compartment having a drop slot for inserting letters therein and a movable front wall member constituting a door for said compartment, said movable wall member having a wall portion extending outwardly and downwardly from the bottom thereof and said wall portion completing, only when said movable wall member is in door shut position, a tubular auxiliary compartment for receiving mail such as rolled newspapers and the like, said auxiliary compartment being positioned adjacent the lower front edge of said letter compartment and extending transversely from side to side of said compartment, and a common partition wall separating said respective compartments, said auxiliary compartment being inclosed throughout its length but having an end opening whereby mail such as rolled newspapers and the like is inserted or withdrawn from a side of said mail box, said partition wall blocking access to said letter compartment despite insertion or withdrawal of such mail.
